ATTORNEY

UNITED STATES PATENT OFFICE

DENIS P. McLAUGHLIN, OF SAN DIEGO, CALIFORNIA

SAFETY ATTACHMENT FOR TYPESETTING MACHINES

Application filed January 7, 1929. Serial No. 330,742.

My invention relates to safety attachments for typesetting machines and the objects of my invention are: First, to provide a safety attachment which may be used with any type-setting machine which has incorporated therein a quick-change mold ejecting apparatus using ejector blades; second, to provide a device of this class which prevents the molds, mold liners, or ejector blades from being broken or ruined due to the ejector blades being set to eject a greater number of ems than the size of the mold; third, to provide a safety attachment of this class which when the mold disc is rotated the ejector blade operating mechanism automatically shifts so that only the ejector blade necessary to eject the smallest mold provided on the mold disc will operate, thus unless the operating mechanism is reset to the proper size mold, the ejector blade would only strike a portion of the slug formed in the mold, breaking the slug, but as the slug can easily be recast and is of comparatively soft metal, no damage is done to the machine and it is only necessary to eject the remaining portion of the slug and recast the line; fourth, to provide a safety attachment of this class which eliminates the constant expense of liners or molds which are ruined for further use every time they are struck by the ejector blade; fifth, to provide a safety attachment in which the lever used to change the width of the ejector blade will not disengage the rack which operates therewith for the setting of the ejector blades if said lever should be accidentally struck; sixth, to provide a safety attachment of this class which does not interfere with the normal use of the typesetting machine; seventh, to provide a safety attachment of this class which is easily installed on the conventional typesetting machine; and, eighth, to provide a device of this class which is simple of construction proportional to its functions, durable, efficient in its action and which will not readily deteriorate or get out of order.

With these and other objects in view as will appear hereinafter, my invention consists of certain novel features of construction, combination and arrangement of parts and portions

as will be hereinafter described in detail and particularly set forth in the appended claims, reference being had to the accompanying drawings and to the characters of reference thereon which form a part of this application in which:

Figure 1 is a fragmentary side elevational view of a typesetting machine showing a portion of my safety attachment in connection therewith with parts and portions thereof in section to facilitate the illustration; Fig. 2 is a fragmentary sectional view of a typesetting machine taken near the ejector blade setting mechanism showing my attachment in connection therewith in elevation; Fig. 3 is an enlarged fragmentary elevational view of my attachment from the line 3—3 of Fig. 2; Fig. 4 is a sectional view thereof through 4—4 of Fig. 2 with parts and portions shown fragmentarily to facilitate the illustration; Fig. 5 is a fragmentary sectional view through 5—5 of Fig. 3 with parts and portions shown in elevation to facilitate the illustration; Fig. 6 is a transverse sectional view through 6—6 of Fig. 5 with parts and portions shown in elevation to facilitate the illustration; Fig. 7 is another transverse sectional view through 7—7 of Fig. 5; and Fig. 8 is an elevational view of my attachment taken at right angles to the views shown in Figs. 1 and 2 with parts and portions in section and essential, adjacent portions of the typesetting machine shown by dotted lines.

Similar characters of reference refer to similar parts and portions throughout the several views of the drawings.

Bracket 1, lever member 2, set screw 3, cam 4, shaft 5, shaft bearings 6 and 7, weight 8, ejector lever 9, upper latch handle 10, lower latch handle 11, springs 12, arm members 13, link members 14 and 15, and double lever member 16, constitute the principal parts and portions of my safety attachment.

In the conventional structure without my safety attachment, when the ejector blade is set for a wider width than the mold, the ejector blades strike the liners which limit the width of the mold bending the liners and jamming them in the slots in which they fit, necessitating many times considerable repair.

in order to again put the mold in condition for use. At other times the ends of the ejector blades are bent so that they must be changed. With my device the slug is the only thing that is damaged and as this may be readily recast, very little trouble is caused by the mistake of the operator.

A bracket 1 is secured to the frame of the typesetting machine below the mold disc pinion gear A of said machine. A lever member 2 is pivotally supported in the bracket 1 by means of a pin 1^a. The one arm 2^a of said lever extends upwardly and is provided with a set screw 3 which extends therethrough in such a manner as to engage the pinion gear A. When the handle B attached to the pinion gear is pulled out the pinion gear causes the lever 2 to pivot about the pin 1^a. The other arm 2^b which is considerably longer than the arm 2^a extends downwardly from the bracket 1 and engages a cam 4 mounted on a shaft 5. The shaft 5 is supported in bearings 6 and 7, the bearing 6 of which is secured to a low, horizontally extending portion of the typesetting machine frame C. The shaft 5 is unsupported as close as possible to the upper side of the extended portion C so as to clear the under side of the vise closing lever D, shown in dotted outline in Figs. 1 and 8 of the drawings. A portion of the shaft 5 extends outwardly from the machine and a weight 8 is mounted thereon which tends to force the cam 4 away from the lever 2. The shaft 5 passes under the vise closing levers and under the vise spring E, shown by dotted outline in Fig. 8. An offset portion 5^a is provided in the shaft 5 in order to clear said spring. The shaft 5 passes under or over other mechanism, not shown, forming a part of the vise mechanism of the machine to the second shaft bearing 7, to be described later.

A second arm F similar to the arm C, extends outwardly from the machine on the opposite side of the vise mechanism from the arm C. Another frame portion G of the typesetting machine extends transversely to the arm F a short distance back of the axis of the rod 5, as shown in Figs. 2 and 4 of the drawings.

Secured to this portion G of the frame is an ejector lever rod bracket H which extends upwardly and backwardly from the frame portion G terminating in a bearing for supporting the ejector rod lever 9. This lever 9 is similar to the conventional ejector lever except for its extended end which is changed in shape slightly so as to facilitate its use in connection with my safety device.

Pivottally mounted upon a pin 9^a which is supported by and extends transversely to the lever 9, by means of downwardly extending ear portions 10^a which straddle the ejector lever 9 is an upper latch handle 10. The ejector lever 9 is enlarged around the pin 9^a as

shown best in Fig. 5 in order to form a suitable support therefor.

The latch handle 10 extends past and above the end of the ejector lever 9. A spring 12 extends between the end of the ejector lever 9 and the under side of the latch handle 10 and tends to force said latch handle away from said ejector lever.

A catch member 10^b is mounted at the one side of said upper latch handle 10. This catch member 10^b is adapted to engage teeth of a rack member J which forms a part of the typesetting machine.

This rack member J on the conventional machine is adapted to hold the ejector lever by means of a latch handle similar to the handle 10 in a predetermined position, the notches therein corresponding to the various ejector blades. When the conventional ejector lever is at the highest point of the rack J, the fewest number of ejector blades are permitted to function. As the lever 9 is lowered relative to the rack, more ejector blades are brought into action.

Pivottally mounted on the same pin 9^a by means of ear portions 11^a is a second or lower latch handle. The ears 11^a extend over the ears 10^a of the upper latch handle. Secured to the side of one of the ear portions 11^a is a catch member 11^b which is adapted to engage teeth on the rack J in a manner similar to the upper latch 10^b. The extended end of the lower latch member projects past the end of the ejector lever 9 and is similar in size and shape to the upper latch handle 10. A spring 12, as in the manner before described, tends to force the lower latch handle 11 away from the ejector lever.

Thus in order to change the position of the lever, it is necessary to move both latch handles towards the lever and disengage both catch members 10^b and 11^b.

Secured to the one side of the upper latch handle 10, preferably on the opposite side from the latch lever 10^b, is an arm member 13. This arm 13 extends towards the pivot point of the lever 9. Connected with the end of the arm 13 is a link member 14.

One of the ear portions 11^a of the lower latch handle 11 is provided with an extended portion 11^c to which is pivotally attached by its one end a link member 15.

A double lever member 16 is secured to the shaft 5 between two portions of a bearing 7, which is secured to or made integral with the ejector lever rod bracket H.

The double lever member 16 is provided with two arms 16^a and 16^b. The arm 16^a is relatively short and is connected to the link member 14 which is secured to the arm 13, connected with the upper latch handle 10. The other, or longer arm, 16^b, is connected to the link member 15, which, in turn, is directly connected to the lower latch handle 11.

As the point at which the link member 14

connects with the arm 13 is relatively near the pivotal point of the ejector member 9 of the arm 16^a which connects with the link member 14 it may be relatively short. Whereas the point at which the link member 15 connects with the lower latch handle 11 is relatively far spaced from the pivotal point of the ejector lever 9, the arm 16^b is made, of course, correspondingly long.

10 The pivotal movement of the double member 16, as indicated by the arrow in Fig. 2 causes the link member 14 to rotate the upper latch member about the pin 9^a, disengaging the catch member 10^b from the rack J. This 15 same movement of the lever 16 pushes upwardly on the link member 15 and rotates the lower latch handle so that its catch member disengages the rack. Continued movement of the lever 16 shifts the ejector lever to its 20 upper position on the rack J, the position at which the minimum number of ejector blades will function.

In order to regulate the movement of the double lever 16 a set screw 16^c is provided 25 which is screwably mounted in a lug 16^d, forming a part of the lever 16. The set screw engages the ejector lever rod bracket when the lever 16 is shifted to its upper position.

The weight 8 tends to lift the double lever 30 16 as soon as the latch members are released from the rack J, and also lessens the rebound of the apparatus.

The operation of my safety attachment is as follows: To change the mold disc from one 35 size mold to another, it is necessary to disengage the pinion A from a pin member which rigidly connects said pinion gear to a shaft. In doing so the lever 2 is caused to rotate about its axis which in turn causes the rotation of the shaft 5. This movement causes 40 the latches 10^b and 11^b to disengage the latch and permit the lever to rise to its upper position. Thus, for example, when the mold has been previously set to form a twelve em slug 45 and is then set for an eight em slug, the ejector lever automatically moves to the position for ejecting a four em slug, or the smallest slug for which the device is set to eject. When the ejector blades only four ems in width 50 strike the slug, the slug breaks and only four ems thereof are ejected. The slug being made of relatively soft material breaks without damaging the ejector blade. All the operator is required to do after the slug is 55 broken is to reverse the machine slightly, set the ejector blade to the proper width and eject the portion of the slug remaining in the mold, then recast the slug.

Though I have shown and described a particular construction, combination and arrangement of parts and portions, I do not wish to be limited to this particular construction, combination and arrangement but desire to include in the scope of my invention the 60 construction, combination and arrangement

substantially as set forth in the appended claims.

Having thus described my invention, what I claim as new and desire to secure by Letters Patent is:

1. In a safety attachment of the class described, the combination with a type setting machine having a mold disc drive pinion and ejector blades operated by an ejector lever, of a rod and lever means operated by said mold disc pinion and engageable with said ejector lever for shifting said ejector lever so as to permit the operation of only a predetermined minimum number of ejector blades.

2. In a safety attachment of the class described, the combination with a typesetting machine having a mold disc drive pinion and ejector blades operated by an ejector lever, of a lever means operated by said pinion gear, a rotatable shaft operated by said lever means, said shaft extending to a point in operative relation to said ejector lever, and link means connecting said ejector lever with said shaft for shifting said ejector lever to a predetermined position when said shaft is actuated by said lever means.

3. In a safety attachment of the class described, the combination with a typesetting machine having a shiftable mold disc pinion and ejector blades, an ejector lever for placing said blades in operative position, and a latch and rack means for holding said lever in various shifted positions, of a rod and lever means operated by said pinion gear and engageable with said latch means for disengaging said latch means from said rack means and shifting said latch and ejector lever to a predetermined position.

4. In a safety attachment of the class described, the combination with a typesetting machine having a shiftable mold disc pinion and ejector blades, an ejector lever for placing said blades in operative position, and a latch and rack means for holding said lever in various shifted positions, of a lever means operated by said pinion gear, a shaft operated by said lever means, said shaft extending to a point in operative relation to said latch means, and link means connecting said shaft with said latch means for disengaging said latch means from said rack and shifting said latch means and said ejector lever to a predetermined position.

5. In a safety attachment of the class described, the combination with a typesetting machine having a shiftable mold disc pinion, ejector blades, an ejector lever for permitting the operation of any number of said ejector blades and a rack means cooperating with said ejector lever, of a latch means mounted on opposite sides of said ejector near the extended end thereof, each of said latch means engageable with said rack means for holding said ejector lever in various shifted positions, and a rod and lever means operated by said

pinion gear and engageable with each of said latch means for disengaging said latch means from said rack and shifting said ejector lever to a predetermined position.

- 5   6. In a safety attachment of the class de-
- scribed, the combination with a typesetting
- machine having a shiftable mold disc pinion,
- ejector blades, an ejector lever for permitting
- the operation of any number of said ejector
- blades and a rod means co-operating with
- 10   said ejector lever, of a latch means mounted
- on opposite sides of said ejector lever near
- the extended end thereof, each of said latch
- means engageable with said rack means for
- 15   holding said ejector lever in various shifted
- positions, a lever means operated by said
- pinion gear, a shaft operated by said lever
- means, said shaft extending to an operative
- 20   position relative to said latch means, link
- members connecting said rod with said latch
- means for permitting the movement of said
- rod to disengage said latch means from said
- rack and shift said lever to a predetermined
- 25   position.

25   7. In a safety attachment of the class de-
- scribed, the combination with a typesetting
- machine having a shiftable mold disc pinion,
- ejector blades, an ejector lever for permitting
- the operation of any number of said ejector
- 30   blades and a rod means cooperating with said
- ejector lever, of a latch means mounted on
- the under side of said ejector lever at the
- extended end thereof, said latch means en-
- gageable with said rack for holding said lever
- 35   in various shifted positions, a rod and lever
- means operated by said pinion gear and en-
- gageable with said latch means for disengag-
- ing said latch means from said rack and shift-
- ing said ejector lever to a predetermined po-
- 40   sition.

40   8. In a safety attachment of the class de-
- scribed, the combination with a typesetting
- machine having a shiftable mold disc pinion,
- ejector blades, an ejector lever for permit-
- 45   ting the operation of any number of said
- ejector blades and a rod means co-operating
- with said ejector lever, of a latch means
- mounted on the under side of said ejector
- lever at the extended end thereof, said latch
- 50   means engageable with said rack for holding
- said lever in various positions, a lever means
- operated by said pinion gear, a shaft oper-
- ated by said lever means, said shaft extend-
- ing to a position in operative relation to said
- 55   latch means, an arm extending from said
- shaft, a link member connecting said arm
- with said latch means for disengaging said
- latch means from said rack and shifting said
- latch and ejector lever to a predetermined
- 60   position.

In testimony whereof, I have hereunto set my hand at San Diego, California, this 21st day of December, 1928.
